DESIGN FOR A SHUTOFF VALVE

Lawrence Jaros, Chagrin Falls, Ohio

Application August 14, 1946, Serial No. 132,506

Term of patent 7 years

(Cl. D91—1)

To all whom it may concern:

Be it known that I, Lawrence Jaros, a citizen of the United States, residing at Chagrin Falls, county of Cuyahoga, and State of Ohio, have invented a new, original, and ornamental Design for a Shutoff Valve, for use with gas stoves and the like, of which the following is a specification, reference being had to the accompanying drawings forming part thereof, and in which drawing:

Fig. 1 is a top plan view of a shutoff valve, embodying my new design;

Fig. 2 is an elevational view of one end;

Fig. 3 is an elevational view of the other end thereof;

Fig. 4 is an elevational view of one side, and

Fig. 5 is an elevational view of the other side thereof.

I claim:

The ornamental design for a shutoff valve, as shown.

LAWRENCE JAROS.
